DE VILLO S. PRATT.
MEANS FOR OPERATING THE LATCHES OF EMERGENCY DOORS AND THE LIKE.
APPLICATION FILED OCT. 10, 1912.

1,056,937.

Patented Mar. 25, 1913.

FIG. 1.

FIG. 2.

FIG. 3.

FIG. 4.

UNITED STATES PATENT OFFICE.

DE VILLO S. PRATT, OF BINGHAMTON, NEW YORK.

MEANS FOR OPERATING THE LATCHES OF EMERGENCY-DOORS AND THE LIKE.

1,056,937.

Specification of Letters Patent.

Patented Mar. 25, 1913.

Application filed October 10, 1912. Serial No. 724,999.

To all whom it may concern:

Be it known that I, DE VILLO S. PRATT, a citizen of the United States, residing at Binghamton, in the county of Broome and State of New York, have invented certain new and useful Improvements in Means for Operating the Latches of Emergency-Doors and the Like, of which the following is a specification.

10 My invention relates to certain new and useful improvements in means for operating the latches of emergency exit doors, and the object of my invention is to provide a construction in which pressure applied 15 against a part attached to the latch in the direction to cause the door to open will turn the latch and unlock the door.

A further object of my invention is to provide a device of this character which will be 20 simple in construction, positive in operation and not unsightly when in position.

With these and other objects in view my invention consists in certain constructions, combinations and arrangements of parts, the 25 preferred form of which will be first described in connection with the accompanying drawings and then the invention particularly pointed out in the appended claims.

Referring to the drawing wherein the 30 same part is designated by the same reference numeral wherever it occurs, Figure 1 is a perspective view of a portion of a door equipped with the preferred form of my invention; Fig. 2 is a cross section through 35 the door, showing my invention in top plan; Fig. 3 is a central longitudinal section through the door; Fig. 4 a perspective view of portions detached and separated and Fig. 5 is a section taken on line 5, 5 of Fig. 2, and 40 looking in the direction of the arrow.

10 designates a door which is hung so as to swing outwardly, or away from the side, illustrated in Fig. 1. The latch for the door comprises a casing 11, having a bolt 12 45 which is pressed outwardly by means of a spring. The inner end of the bolt is shown as forked, and the forks at their ends carry the legs 13, adapted to be engaged by the cam sections 14, 14 supported on the rotatable sleeve 15. The sleeve 15 is preferably provided with a square socket 16 to receive the end of the operating device.

The lock or latch so far described forms no part of my invention and is merely shown 55 for the purpose of illustrating the operation of my invention.

The means for turning the sleeve 15 comprises a body portion 17 from one end of which extends a squared portion 18 adapted to enter the square openings 16 of the 60 sleeve 15. The body portion 17 is formed with a pair of spiral longitudinally extending cams 19, and at the outer end the body portion is preferably provided with the head 20. From this construction it will be seen 65 that rotation of parts 17 will rotate the sleeve 15 and operate the bolt of the latch. Hinged to the inner face of the door is a bar 21, the bar being hinged to the door at one end by means of the hinge 22, and carrying at its opposite end the fork 23, the prongs of the fork being inwardly turned, as shown at 24, and the portions 24 are adapted to engage the spiral cams 19 on the body portion 17. 75

25 indicates a spring secured at one end to the door and bearing at its other end against the bar 21, whereby the parts are normally held in position, with the bolt extending from the door as shown in Fig. 1. 80 When, however, the bar 21 is pressed, the inwardly extending portions 24 will engage the cams 19, rotating the sleeve 15 and operating to draw the bolt and unlock the door.

In order to support the bar 21 and cause 85 it to move I have shown the bars guided by a bracket 26 secured to the door and on which the bar slides. I have also shown a latch 27 pivoted to the door and adapted to be swung into the path of one of the cams 90 19, as best shown in Fig. 5, to lock the bolt in position and prevent the door from being latched.

I realize that considerable variation is possible in the details of construction and arrangement of parts without departing from the spirit of my invention, and I therefore do not intend to limit myself to the specific form shown and described. 95

Having thus described my invention what 100 I claim as new and desire to secure by Letters Patent is:

1. In a means for operating the latches of emergency doors and the like, the combination with a door, of a lock having a 105 bolt, a rotatable part adapted to operate the bolt, a part extending from said rotatable part and provided with a spiral cam, a bar pivoted to the door, and a fork carried by the bar to engage said spiral cam, said 110 parts being constructed and arranged to cause the bolt to be withdrawn and the door

unlocked when the bar is pressed toward the door.

2. In a means for operating the latches of emergency doors and the like, the combination with a door, of a lock having a bolt, a rotatable part adapted to operate the bolt, a part extending from said rotatable part provided with a spiral cam, a bar pivoted at one end to the door, a fork carried by the other end and having inwardly projecting extensions adapted to engage the spiral cam, and a spring interposed between the bar and the door, said parts being connected and arranged to cause the bolt to be withdrawn and the door unlocked when the bar is pressed toward the door.

3. In a means for operating the latches of emergency doors and the like, the combination with a door, of a lock having a bolt, a rotatable sleeve adapted to engage the bolt to operate the same, a part connected to said rotatable sleeve and provided with a spiral cam, said part being also provided with an outwardly extending head, a bar pivoted to

the door at one end, a fork extending from the opposite ends of the bar, said fork being provided with inwardly projecting portions adapted to engage the spiral cam.

4. In a means for operating the latches of emergency doors and the like, the combination with a door, of a lock having a bolt, a rotatable part adapted to operate the bolt, a part extending from said rotatable part and provided with a spiral cam, a bar pivoted to the door, a fork carried by the bar to engage said spiral cam, said parts being constructed and arranged to cause the bolt to be withdrawn and the door unlocked when the bar is pressed toward the door, and means adapted to be swung into the path of said cam to lock the bolt in position and prevent the door from being latched.

In testimony whereof I affix my signature in presence of two witnesses.

DE VILLO S. PRATT.
